METAL SPRING COVER

Frederick H. Schlesser, Chicago, Ill., assignor to
 Ajax Spring Stabilizer Company, Brookline,
 Mass., a corporation of Illinois

Application January 3, 1933. Serial No. 649,752

4 Claims. (Cl. 267—37)

This invention relates to improvements in metal spring covers for laminated springs and the principal object of the invention is to provide a metal spring cover formed of a plurality of units which can be economically constructed and readily applied to the spring by unskilled labor and without the use of special tools.

It is difficult to apply usual metal spring covers to springs of automobiles after the automobile has been assembled and in usual practice spring covers are therefore applied to the spring at automobile factories having suitable mechanism for loading or straightening the springs to enable the spring covers to be easily applied to them.

Another object of the present invention is to provide a spring cover comprising a series of fabricated units which can be readily applied to the springs of an automobile after the automobile has been assembled. More particularly the invention relates to improvements in spring covers comprising a plurality of sheet metal units fabricated to conform to corresponding sections of the spring in which each unit is formed from a sheet of metal bent to provide a central panel slightly wider than the spring to cover one of the horizontal faces thereof and side panels slightly wider than the thickness of the spring having inwardly extending flanges to overlie the other horizontal face of the spring in the same plane with locking plates overlying the flanges and provided with releasable locking means for connecting said plates to said flanges remote from the edges thereof.

A further object of the invention is to provide a novel form of clip cover adapted to be used in combination with the spring cover units above described.

These and other objects and features of the invention will more fully appear from the following description and accompanying drawing and will be more particularly pointed out in the claims.

A preferred embodiment of the invention is illustrated in the accompanying drawing, in which:

Fig. 1 is a perspective view of one end of an inverted spring having a cover embodying the invention applied thereto.

Fig. 2 is a transverse sectional view of the spring cover and spring illustrated in Fig. 1.

Fig. 3 is a perspective view of one of the spring cover units and illustrating locking tabs extending outwardly from the flanges of the spring cover.

Fig. 4 is a perspective view of a preferred form

of locking plate having a plurality of pairs of slots adapted selectively to engage the tabs of the construction illustrated in Fig. 3.

Fig. 5 is a side elevation of approximately one-half of the semi-elliptical spring having spring cover units embodying the present invention applied thereto and also including clip covers embodying the present invention held in place by adjacent spring cover units.

Fig. 6 is a detailed perspective view of assembled clip cover units embodying the present invention.

Fig. 7 is a detailed longitudinal vertical sectional view showing the relative positions of the assembled clip cover and spring cover units and also showing the fabric wrapping for the spring within the cover.

The spring cover comprises a plurality of units fabricated from sheet metal to conform to corresponding sections of the spring having a flat central panel 1, side panels 2 and 3 bent at right angles thereto and tapered longitudinally to conform to the thickness of the spring and of a width slightly greater than the thickness of the spring with flanges 4 and 5 bent at right angles to the respective side portions 2 and 3 and adapted to overlie the other horizontal face of the spring. The flanges 4 and 5 when applied to the spring lie in the same plane with the free edges thereof in close juxtaposition and preferably in abutment, although the edges may be more or less separated as the flanges desirably lie along the under surface of the spring. Preferably adjacent units are so arranged that the smaller end of each unit, except the end units, telescopically engages within the larger end of an adjacent unit.

Each unit is locked upon the spring by a plate which overlies the flanges and is releasably secured to said flanges remote from the edges thereof. In the preferred construction, tabs 6 and 7 are punched from the respective flanges preferably centrally of their length and bent up a bit as illustrated in Fig. 3. Separate members having suitable heads, however, may be inserted through the flanges to extend outwardly therefrom to provide locking members.

A suitable locking plate of any desired width having a pair of slots adapted to receive the tabs 6 and 7 or other locking members may be employed to complete the lock, the tabs being inserted through the slots in the plate and thereafter turned down upon the plate in such a manner as to secure the plate firmly in locking position.

Inasmuch as springs may differ slightly in width or tabs may be differently spaced apart on flanges of different spring covers, the locking plate desirably is provided with a plurality 5 of pairs of slots, as illustrated in Fig. 4, which illustrates a plate 8 having three pairs of slots 9-9, 10-10, arranged in parallelism and a pair of slots 11-11 arranged at right angles thereto. Any one of these pairs of slots may be utilized to 10 receive the locking tabs 6 and 7 or a slot of one of the pairs 9-9 may be employed with one of the slots of the pair 10-10, thus providing a wide range of adjustability. When the tabs have been inserted through the selected pair of slots, 15 they may be turned downwardly by merely pressing, hammering or otherwise deforming the tabs.

When it is desired to remove the spring cover, these tabs may be bent into vertical position, as 20 illustrated in Fig. 3, the locking plate removed, and the spring cover readily expanded and removed from the spring.

Another object of the invention is to provide a suitable clip cover for use in connection with the spring cover unit above described. Such a 25 clip cover is illustrated in detail in Fig. 6 and in assembled position in Figs. 5 and 7. The clip cover illustrated in Fig. 6 preferably comprises three independent sections each having a transverse channel to embrace and cover the corresponding portion of the clip with flanges extending 30 from the channel-shaped portion longitudinally of the spring. As illustrated in Figs. 6 and 7, the clip cover comprises a sheet metal section having a central channel portion 12 with flanges 35 13 and 14 corresponding to the width of the spring extending from said channel portion 12 longitudinally of the spring. Two side members of identical construction will be employed each having a central channel portion 15 with flanges 40 16 and 17 extending longitudinally of the spring and of a width corresponding to the width of the spring or to the length of the legs of the spring clip.

In assembling the clip cover on the spring, the 45 top and side members may be applied to the clip and the adjacent spring cover units then placed upon the spring telescopically to enclose the flanges 16 and 17 of the clip cover, respectively. Desirably the spring is enwrapped with a lubricant-containing material such as an oil or grease-soaked canvas 18 before the application of the 50 spring cover units to the spring. If desired an additional sheet metal section, similar to the section having a channel portion 12 with flanges 55 13 and 14, may be applied to the under surface of the spring to enclose the bar which connects the lower ends of the legs of the clip, as illustrated in Fig. 7.

In order to protect the flanges of the spring 60 cover units which desirably extend along the under face of the spring from frictional wear by engagement of the ends of the progressively shorter laminations of the spring, a flat plate 19 desirably is interposed between the flanges 4 65 and 5 and the spring or the wrapping which encases the spring. The ends 20 of the plate 19 desirably are bent over the ends of the spring cover units which enclose the base and end of the 70 spring and serve both to complete the closure of the space between the edges of the flanges and to prevent longitudinal displacement of the spring units.

It will be understood that the particular embodiment of the invention herein described is of an illustrative character and various changes in form, construction and arrangement of parts may be made within the spirit and scope of the 80 following claims.

Having thus described the invention, what is claimed as new, and desired to be secured by Letters Patent, is:

1. A spring cover for laminated springs comprising a plurality of sheet metal units fabricated to conform to corresponding sections of the spring and having a central panel slightly wider than the spring, to cover one of the horizontal faces thereof, side panels slightly wider than the thickness of the spring having inwardly extending flanges to overlie the other horizontal face of the spring with the free edges of said flanges in the same plane, locking plates overlying said flanges and releasable means for connecting said locking plates to said flanges remote from the edges thereof. 85

2. A spring cover for laminated springs comprising a plurality of sheet metal units fabricated to conform to corresponding sections of the 100 spring and having a central panel slightly wider than the spring, to cover one of the horizontal faces thereof, side panels slightly wider than the thickness of the spring having inwardly extending flanges to overlie the other horizontal 105 face of the spring with the free edges of said flanges in the same plane, metallic locking members extending outwardly from each flange remote from the edge thereof and locking plates overlying said flanges having means releasably to 110 engage said locking members.

3. A spring cover for laminated springs comprising a plurality of sheet metal units fabricated to conform to corresponding sections of the 115 spring and having a central panel slightly wider than the spring, to cover one of the horizontal faces thereof, side panels slightly wider than the thickness of the spring having inwardly extending flanges to overlie the other horizontal 120 face of the spring with the free edges of said flanges in the same plane, metallic tabs punched from the respective flanges and extending outwardly therefrom at a distance from the edges thereof, locking plates having a pair of slots to receive the respective tabs adapted when the 125 tabs are inserted in said slots and bent down to lock said units upon the spring.

4. A spring cover for laminated springs comprising a plurality of sheet metal units fabricated to conform to corresponding sections of the 130 spring and having a central panel slightly wider than the spring, to cover one of the horizontal faces thereof, side panels slightly wider than the thickness of the spring having inwardly extending flanges to overlie the other horizontal 135 face of the spring with the free edges of said flanges in the same plane, metallic tabs punched from the respective flanges and extending outwardly therefrom at a distance from the edges thereof, locking plates having a plurality of pairs 140 of differently spaced slots selectively adapted to receive the tabs of the respective sections and when the tabs are inserted in the proper pair of slots and bent down to lock the units upon the spring. 145

FREDERICK H. SCHLESSER.
